CLAIM

The ornamental design for a robot, as shown and described.

DESCRIPTION

FIG. 1 is a front perspective view of a robot in accordance with the present design;
FIG. 2 is a front view thereof;
FIG. 3 is a rear view thereof;
FIG. 4 is a left-side view thereof;
FIG. 5 is a right-side view thereof;
FIG. 6 is a top view thereof; and,
FIG. 7 is a bottom view thereof.

The broken lines show portions of a robot that form no part of the claimed design.
